A. L. WALLAU

FILLER FOR CIGAR LIGHTERS

Filed Feb. 21, 1927

UNITED STATES PATENT OFFICE.

ALEXANDER LEE WALLAU, OF CEDARHURST, NEW YORK.

FILLER FOR CIGAR LIGHTERS.

Application filed February 21, 1927. Serial No. 169,899.

This invention relates to cigar lighters and the like and more particularly to instrumentalities for filling them with a combustible liquid.

5 The commercial type of cigar lighters comprising a wick extending into an inflammable liquid with a pyrophoric alloy spark producing mechanism operate quite satisfactorily so long as they are filled with 10 certain selected liquids such, for example, as benzene. The quantity required to fill the lighter is quite small—in the neighborhood of three quarters of an ounce and the inflammable liquids are not usually at hand 15 when refilling is required. Furthermore, the liquid is kept absorbed in an absorbent medium and it requires a certain material length of time to saturate it. It is therefore a considerable nuisance to fill these 20 lighters by hand, as it requires that the liquid be furnished to the absorbent almost drop by drop and when the filling is completed quite a surplus liquid is left in the reservoir of the lighter, which will thereafter spill out objectionably unless previously drained.

It is an object of this invention to provide 30 a device in accordance with which such articles may be readily filled with liquid in a practical and efficient manner. It is a further object to provide such a device which will be sensitive to operate only in the presence of the article to be filled, so that the liquid will not be needlessly wasted. It is a 35 further object to produce a device which will be made in ornamental and attractive form for display upon cigar stands and the like and in which the operating parts will be sufficiently visible to excite curiosity and 40 stimulate interest.

It is a further object to produce such a device that the lighter will be completely filled, but that will only consume the amount of liquid which is required for actually 45 filling the lighter.

The invention accordingly comprises the features of construction, combinations of elements, and arrangement of parts which will be exemplified in the construction hereinafter set forth and the scope of the application of which will be indicated in the 50 claims.

For a fuller understanding of the nature and objects of the invention reference should 55 be had to the following detailed description

taken in connection with the accompanying drawing in which:

Figure 1 is a vertical, sectional view of the device along the lines 1—1 of Figure 2 and

Figure 2 is a vertical section along the 60 lines 2—2 of Fig. 1.

Figure 3 is a top plan view ready for the application of the lighter.

Figures 4, 5, 6 and 7 are details of a valve control.

In the drawings the numeral 1 comprises a body portion supported on a base 2 adapted to rest upon a stand of a cigar store. The body portion comprises, generally, a liquid reservoir 3, a valve compartment 4 and a coin-control mechanism 5. A convenient method of insuring that the lighter shall be completely filled with liquid without the presence of any surplus liquid is to cause the lighter to be reverted below the liquid level 75 while connected to the reservoir and subsequently to raise it above the liquid level inverted while still connected to the reservoir. In this manner the liquid originally 80 completely fills the compartment, permitting the absorbent to soak up the maximum quantity. Thereafter, upon inversion all surplus may drain back into the reservoir. This principle is, therefore, employed in the specific embodiment of the invention herein disclosed. To accomplish this result there is mounted in the body portion 1 a shaft 10 carrying a casing 11 having attached thereto a stem 12 carrying a nipple 13 for the reception of the lighter 14. The shaft 10 may have an operating handle 15 and this construction is such that when the handle 15 is rotated one half revolution the stem, nipple and lighter are carried from the inverted position shown in dotted lines in Fig. 2 85

downwardly about the axis of the shaft 10 to the reverted position within the valve compartment, as shown in Fig. 1 in dotted lines. The casing 11 includes an operating mechanism which communicates with the liquid within the reservoir 3 by an orifice 16 and communicates with the interior of the lighter 14 through the bore of the stem 12. This valve is arranged to open communication between the reservoir and the lighter 90 when the lighter is in the completely reverted position, but to maintain this communication open during the reinversion of the lighter until the lighter has again passed above the liquid level and subsequently to 95

close that communication when the lighter is completely inverted. The mechanism for accomplishing this, as herein illustrated, is as follows:—

5 A disk 17 journalled upon the shaft 27 fits within a boss 18 on the inner side wall of the reservoir within the valve casing. This disk 17 has its outer face mating with the side wall on the interior of the boss to form a liquid-tight joint. The inner face of the orifice 16 serves as a valve port and the disk 17 carries an opening 19 arranged to cooperate with the port 16 when in one position and to close the same when the disk is partly rotated. The disk 17 carries a depending arm 20 in position to be engaged by the lighter when the lighter is in almost the completely reverted position. Thereafter the continued rotation of the handle 15 to 10 the completed reverted position will rotate the disk 17 to bring the port 19 into cooperation with the port 16 to open the valve. A plate 21 fits upon the shaft 27 but is held from rotation by lugs 22 fitting in recesses 15 23 in the boss 18. This plate carries a substantially semicircular slot 24 adapted to afford communication between the port 19 and the lighter at all times during the reversion and inversion of the same. The casing 30 11 has a port 25 in direct communication with the bore of the stem 12 and arranged to be at all times in communication with the semi-circular slot 24. The casing 11 may be threaded upon its interior, as shown at 35 26, to enable it to be connected to a rod 27 controlled by a spring 28 and a nut 29, so that the valve parts may be retained at all times in assembled position. The casing 11 has a depending lug 30 in position to engage 40 the arm 20 just before the lighter resumes its complete inversion, so that the completion of the inversion will move the arm 20 to close the valve.

I preferably arrange the valve compartment in a quadrantal form such that the lighter will be enclosed within it from substantially the beginning of its turning movement. This prevents tampering with the device by removing the lighter while the 45 valve is open to permit the liquid to escape from the reservoir. Moreover, the quadrantal shape makes it difficult to get access to the lever 20 to open the valve except in the normal way. This quadrantal valve chamber is preferably of not much more than sufficient width to receive the width of the lighter. On this account, it is desirable that the nipple 13 shall be arranged to make a 50 liquid-tight joint regardless of the lie of the threads in the lighter. This may be readily accomplished by imposing upon the nipple a soft rubber gasket 31 capable of compression for more than one-half the pitch of the thread. The greater part of the 55 machine is preferably of glass, or provided

with glass windows, so that the operating mechanism is exposed to view.

In order to prevent the mischievous opening of the valve by the insertion of a pencil or the like article to engage the lever 20, there may be provided a locking bar 41 operated by the coin-control mechanism. This bar normally stands in the path of movement of the lever 20 but is operated from the coin-control mechanism to be withdrawn from the pathway to permit the lever to be moved.

The machine is designed for coin-control and the coin-control mechanism 5 is arranged to prevent the rotation of the handle 15, except upon the insertion of an appropriate coin, in the slot 40. Such coin-control mechanisms, however, are all well known in the art and on that account the present disclosure is not encumbered with detailed construction. The reservoir 3 is preferably provided with a filling opening 42 closed by a cap 43.

The device as described makes an attractive display for a sign or the like and to this end there may be attached, at any convenient point, as for example at the front, a suitable plate 44 to carry advertising matter.

Since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. A device for filling cigar lighters and the like, including a reservoir, connections adapted to connect said reservoir to a lighter, means for controlling the flow of liquid through said connections operated by the presence of the lighter.

2. A device for filling cigar lighters and the like, including a reservoir, connections between said reservoir and said lighter adapted to support said lighter above the level of the reservoir to permit any surplus liquid to redrain into the reservoir.

3. A device for filling cigar lighters and the like, including a reservoir, connections between said reservoir and said lighter adapted to support said lighter below the level of the reservoir to permit liquid to flow into said lighter.

4. A filler for cigar lighters and the like, including in combination a liquid reservoir,

means for connecting said reservoir to a cigar lighter including a nipple to which the cigar lighter may be attached, said nipple being movable from a position to support 5 the lighter above the level of the reservoir to a position to support it below the level of the reservoir.

5. A filler for cigar lighters and the like, including, in combination, a liquid reservoir, 10 means for connecting said reservoir to a cigar lighter including a nipple to which the cigar lighter may be attached, said nipple being movable from a position to support the lighter above the level of the reservoir to a position 15 to support it below the level of the reservoir, and a valve for admitting liquid to the lighter when it is below the level of the reservoir.

6. A filler for cigar lighters and the like, 20 including, in combination, a liquid reservoir, means for connecting said reservoir to a cigar lighter including a nipple to which the cigar lighter may be attached, said nipple being movable from a position to support the 25 lighter above the level of the reservoir to a position to support it below the level of the reservoir, and a valve for admitting liquid to the lighter when it is below the level of the reservoir, and means for operating said 30 valve controlled by the presence of the lighter.

7. A filler for cigar lighters and the like, including a reservoir for liquid, a support 35 for a lighter or the like having a bore connected with said reservoir and means for closing said bore operable only by the presence of the lighter.

8. A filler for cigar lighters and the like including a reservoir, means for connecting 40 said reservoir to the lighter, including a nipple movable vertically with respect to said reservoir, whereby it may be brought below the level of the liquid to fill the lighter until the absorbent therein is saturated and may 45 subsequently be lifted above the level of the reservoir, to drain off surplus liquid.

9. A filler for cigar lighters and the like, including a reservoir, connections between 50 said reservoir and said lighter including a threaded nipple and means associated with said nipple for adjusting the effective length of the thread for more than one-half the pitch of the thread whereby the lighter may be firmly supported in liquid tight relation 55 for one-half revolution of the lighter.

10. A filler for cigar lighters and the like, including a reservoir, connections adapted 60 to connect said reservoir to a lighter, including means for effecting relative vertical motion between said lighter and the liquid level

in said reservoir, whereby said lighter may be both above and below said liquid level, means for controlling the flow of liquid from said reservoir, and means for opening said controlling means when said lighter is below 65 the liquid level and for closing said control means when the lighter is above the liquid level.

11. A filler for cigar lighters and the like, 70 including a reservoir and means for connecting said reservoir to the lighter, including a threaded nipple adapted for connecting to the lighter, and means adjustable for more than one-half the pitch of the thread for making a liquid tight lighter supporting connection to said lighter while said lighter is turned through one-half revolution.

12. A filler for cigar lighters and the like, 75 including a reservoir adapted to contain a liquid, means adapted to connect said reservoir to a cigar lighter, and means for controlling the flow of liquid through said connecting means, including a valve, a depending arm for operating said valve in position to be encountered by said lighter to be moved thereby.

13. A filler for cigar lighters and the like, 80 including a reservoir for a liquid, means adapted to connect said reservoir to a lighter, a valve for controlling the communication 85 between said reservoir and said lighter, including means for supporting the lighter during movement above and below the liquid level, coin-operated means for controlling said movement and coin-operated means for 90 locking said valve.

14. A filler for cigar lighters and the like which contain an absorbent medium, including, in combination, a reservoir for liquid, 100 means to connect said reservoir with the lighter completely to fill the latter and to drain the said lighter of all unabsorbed liquid.

15. A filler for cigar lighters and the like containing an absorbent material including, 105 in combination, a reservoir for liquid, flexible connection between said reservoir and said lighter including means adapted to project the lighter below and to raise it above the liquid level in the reservoir and valve 110 control mechanism adapted to permit free passage of liquid to the lighter from the reservoir while the lighter is below the liquid level and to permit surplus liquid to drain back into the reservoir after the lighter is 115 raised above the liquid level and means for closing the connection after said draining.

In testimony whereof I affix my signature.

ALEXANDER LEE WALLAU.
